UNITED STATES PATENT OFFICE.

ELLIOT Q. ADAMS, OF BERKELEY, CALIFORNIA, BY MESNE ASSIGNMENTS DEDICATED
TO THE PEOPLE OF THE UNITED STATES FOR THEIR FREE USE AND ENJOYMENT.

MACHINE USED FOR THE PROCESS OF SUBLIMATION.

Application filed September 18, 1919. Serial No. 324,730.

(FILED UNDER THE ACT OF MARCH 3, 1883, 22 STAT. L. 625.)

To all whom it may concern:

Be it known that I, ELLIOT Q. ADAMS, a citizen of the United States of America, and an employee of the Department of Agriculture, residing in the city of Berkeley, county of Alameda, State of California (whose post-office address is Department of Agriculture, Washington, D. C.), have invented a new and useful Improvement in the Machine Used for the Process of Sublimation.

This application is made under the act of March 3, 1883, chapter 143 (22 Stat., 625), and the invention herein described and claimed may be used by the Government of the United States or any of its officers or employees in the prosecution of work for the Government, and any person in the United States, without payment to me of any royalty thereon.

In the purification of substances by sublimation the current of gas charged with volatile substances has been caused to move through large numbers of small orifices, arranged in approximately the same plane in a sheet, plate or screen, the least volatile constituents separating or congregating or crystallizing on the edges or adjacent to the orifices. The material collecting on the screens or on the orifices has been removed by shaking or jarring the screens or by scraping or brushing by hand intermittently or continuously.

I have found that the removal of the material collecting on the screens can be better accomplished by arranging the screens as a series of concentric cylinders, or half-cylinders, and causing brushes to revolve, or oscillate, about the axis of the cylinders, passing across the face of the screens at each revolution, or oscillation.

This arrangement possesses the additional advantage that, being radially symmetrical, the temperature tends to be uniform over the entire surface of each screen, which is not the case when the screens are disposed otherwise.

This method of operation is illustrated in the accompanying drawings, Figs. 1 to 4, inclusive, showing an apparatus with hemicylindrical screens, and Figs. 5 to 8, inclusive, showing an apparatus with cylindrical screens.

Similar letters refer to similar parts in the different views of the same apparatus.

The operation of the two types of apparatus will now be described in detail.

Figs. 1 to 4 show sections of the apparatus with hemicylindrical screens, the sections being taken at the planes indicated (in the other views) by Y'Y', Z'Z', Q'Q' and V'V', respectively.

The current of heated gas charged with the volatile substances enters the apparatus through the port, I, in the wall, W, passing in succession through the concentric compartments, C₁, C₂, C₃, C₄, C₅, C₆, C₇, which are separated by the screens S₁, S₂, S₃, S₄, S₅ and the perforated wall P, C₇ is bounded externally by the outer shell, E, of the apparatus. The perforations in P are so disposed as to equalize the gas flow over the entire area of the screens. From C₇ the gas passes into a collecting dome, D, and leaves the apparatus at O. The partition, X, and the flange, J, prevent the leakage of gas into or from the apparatus. Loss of heat into the outgoing gas in D, is prevented by the heat insulating material at L.

The material collecting on the screens, S₁, S₂, S₃, S₄, S₅ on the inside of the perforated wall, P, and on the roof, L, is brushed off by the brushes, B, (which are carried on frames T₂, T₃, T₄, T₅, T₆, which in turn are attached to the oscillating arm A) and swept along the floor, F₁, until it falls into the hoppers, H₁, H₂, H₃, H₄, H₅ and H₆, from which it may be removed by drawing the slides, N.

The floor, F₁, is supported by the piers, U.

The brush arm, A, is caused to oscillate by the rack, R, acting on gear G₃ (attached to A). R is actuated by the motor, M, acting through the gears, G₁ and G₂, and the connecting rod, K.

Figs. 5 to 8, show sections of the apparatus with cylindrical screens, the sections being taken at the planes indicated (in the other views) by A'A'B'B', A'A', B'B' and Z, respectively. The apparatus is built upon a floor M¹, supported by piers, P', P''. The gas current entering at G passes over the material to be sublimed at H', H, is deflected downward by the baffle, W' and

passes in succession through the screens, D^1 , D^2 , D^3 , D^4 , and finally is allowed to bubble through the water seal, N' , or is carried down through the floor M^1 by ducts (not shown).

The heat necessary for the sublimation is supplied by the burners U' , supplied by pipe Q^1 , the burned gases being carried from the combustion chamber, Z , through the 10 flue F .

The material to be purified is placed in the funnel, R' , is fed into the apparatus by the spiral feed, V , melted by heat from F and flows in succession over the annular 15 trays, H' , H , finally collecting in the space, Y , from which it drips out by tube, Q . The opening at X' prevents siphoning. The trays H , are supported from the outer wall, E , of the vaporizing apparatus, the 20 trays H' , from F .

The funnel, R , the roof, S , the outer shell, C , the screens, D^1 and D^3 and the brushes J^2 are fastened together, supported on rollers in the trough, N' , and caused to rotate, 25 as a unit, by the motor L' acting through the worm, K^1 and worm wheel K_2 . The motor rests on the shelf M^2 . The screens D^2 and D^4 and the brushes J^1 are attached to the floor.

30 In this way the rotation of the movable parts of the apparatus causes brushes J^2 to pass over the floor M^1 and the stationary screens D^2 , D^4 , while screens D^1 and D^3 , the roof S , and the outer shell C , move past the stationary brushes J^1 . All the material 35 collecting on the screens is thus removed and falling to the floor is swept into the hoppers, I_1 , I_2 , I_3 , I_4 , I_5 , from which it may be removed by drawing the slides, XX .

40 Having now fully described my invention, what I claim and desire to protect by Letters Patent is—

1. In apparatus of the character set forth, the combination with a series of communicating condensing chambers, one within the other, of means for introducing vapors to be condensed into the inner chamber and permitting their outward flow through the others, means for securing different temperatures in the different chambers, and means for separately collecting the different materials condensed in the different chambers respectively and separately withdrawing the same.

55 2. In apparatus of the character set forth, the combination with a casing comprising a rear wall, an arcuate wall having its ends associated with the rear wall, and a top and bottom, of a series of arcuate substantially concentric foraminous walls within the casing, having their ends associated with the rear wall defining a plurality of 60 chambers, means for introducing vapors to be condensed into the innermost chamber, and means for permitting the escape of the

unaffected vapors from the outermost chamber.

3. In apparatus of the character set forth, the combination with a series of communicating condensing chambers, one within the other, of means for introducing vapors to be condensed into the inner chamber and permitting their outward flow through the others, means for causing the fractional distillation of the vapors in the 70 different chambers, and means for detaching the condensed materials from the walls of the chamber, separately collecting the same, and permitting their separate withdrawal.

4. In condensing mechanism of the character set forth, the combination with a casing, of means for introducing vapors to be condensed into the casing, means for permitting the escape of the residue, substantially circular screens in the casing between the introducing and escape-permitting means, brushes acting against the screens, means for effecting a complete relative rotation between the screens and brushes, and means operating over the bottom between the screens for separately collecting the materials condensed and deposited in the different compartments formed by the screens and separately discharging the 75 same from the casing.

5. In apparatus of the character set forth, the combination with a substantially cylindrical condenser casing, of substantially cylindrical foraminous walls, one within the other in the casing, and vaporizing means within the innermost wall delivering into the space within said wall.

6. In apparatus of the character set forth, the combination with a cylindrical condensing casing having a rotatable top, of substantially cylindrical screens hung from the top and disposed concentrically one within the other, an upright axially disposed conduit for a heating medium extending through the casing vaporizing means surrounding the conduit and arranged within the innermost screen, said vaporizing means delivering into the space within said innermost screen, a hopper carried by the top and delivering into the vaporizer, and feeding means carried by the vaporizer and located in the hopper.

7. In apparatus of the character set forth, the combination with a condenser casing comprising relatively rotatable sections, of substantially cylindrical screens arranged one within the other and alternately carried by the different sections, means for introducing vapors to be condensed on the screens, and means for removing the materials from said screens.

8. The combination with a casing having a top and bottom, side walls and foraminous partitions forming chambers, one within the other, of a heater passing through the 120

innermost chamber, means for passing a gaseous vehicle and a substance to be vaporized along the heater and causing them to be commingled while heated, means for discharging the commingled and heated vapors into the innermost chamber and causing the same to flow outwardly through the other chambers.

9. In condensing mechanism of the character set forth, the combination with a casing including a side wall and top and bottom walls, one of the two latter being rotatable, and said bottom wall constituting a support for material condensed in the casing of a

continuous screen carried by one wall, a brush operating on the screen and carried by the other wall, means for relatively rotating the top and bottom walls and means for introducing vapors to be condensed into the casing.

10. In testimony whereof, I affix my signature in the presence of two subscribing witnesses.

ELLIOT Q. ADAMS.
